UNITED STATES PATENT OFFICE

LEO V. STOELTZLEN, OF ERIE, PENNSYLVANIA, ASSIGNOR TO REED MANUFACTURING COMPANY, OF ERIE, PENNSYLVANIA, A CORPORATION OF PENNSYLVANIA

DIESTOCK

Application filed August 29, 1929. Serial No. 389,276.

Die stocks are ordinarily provided with a body having a die-receiving socket and usually the body is provided with a guiding device which is inserted into the body from the rear thereof. Ordinarily the guide is changed with the die arranged in the socket. The present invention provides an improved guide which may be inserted through the die stock and is secured in the body as the die is secured. The guide is further provided with openings through it through which chips may pass. This means also assures bringing the guide directly up to the rear of the die so that material, such as pipe being threaded, is accurately centered as the die is started and maintained in alinement as the die is backed off. Features and details of the invention will appear from the specification and claims.

A preferred embodiment of the invention is illustrated in the accompanying drawing as follows:—

Fig. 1 shows the die stock with the die removed.

Fig. 2 a section on the line 2—2 in Fig. 1.
25 Fig. 3 a perspective view of the guide.

1 marks the body, and 2 the shank of the body on which is arranged a ratchet ring 3 from which a handle 3a extends. Ratchet mechanisms 3b are arranged on the ring and operate in the usual manner on the shank.

A die stock 4 is formed in the body and receives a solid die 5. The die rests on a seat 6 and is secured in place by screws 7. A guide socket 8 is arranged immediately under the die stock 4. A guide is formed with a guide tube 9 through which the pipe is carried to the die throat. Radial blades 10 extend from the guide tube and these are provided with outwardly extending shoulders 11 which rest in small notches 12 in the bottom wall of the socket 8. The guide plates fit in an opening 13 extending through the shank. With this structure, when the die 5 is changed the guide may be picked out of its socket and a guide of the size desired dropped in place. The shoulders 11 dropping into the notches 12 lock the guide against turning with the pipe. When the die is secured in place it also secures the guide in place. The opening through the plates gives ample room

for chip disposal. The guide extending from the die socket operates on the pipe practically up to the throat of the die.

What I claim as new is:—

1. In a die stock, the combination of a body having a die-receiving socket and a guide-receiving socket opening through the die-receiving socket; a guide in the guide-receiving socket insertable through the die-receiving socket, said guide comprising a guide tube and radiating projections providing an opening through the guide outside of the guide tube, said radiating projections being seated in the guide socket; a die in the die socket securing the guide in the guide socket; and means securing the die in the die socket. 55

2. In a die stock, the combination of a body having a die-receiving socket and a guide-receiving socket opening through the die-receiving socket, said guide-receiving socket having a seat with notches therein; a guide having a guide tube with radial projections, said projections having shoulders seated in said notches; a die in the die-socket securing the guide in place; and means securing the die in the die socket. 70

In testimony whereof I have hereunto set my hand.

LEO V. STOELTZLEN.
